Specification for Design.

Patented Mar. 21, 1916.

Application filed March 27, 1915. Serial No. 17,545. Term of patent 7 years.

To all whom it may concern:

Be it known that I, BENJAMIN B. HATCH, a citizen of the United States, residing at Boston, in the county of Suffolk and State of Massachusetts, have invented a new, original, and ornamental Design for Signal-Boxes, of which the following is a specification, references being had to the accompanying drawing, forming part thereof.

In the drawings: Figure 1 is a front elevation of a signal box showing my new design; and Fig. 2 is a side elevation thereof.

What I claim is:

The ornamental design for a signal box, as shown.

BENJAMIN B. HATCH.
